Pierre Barnes
ATTORNEY

UNITED STATES PATENT OFFICE.

IRA LEE, OF SEATTLE, WASHINGTON, ASSIGNOR TO WILLIAM J. LEE, OF SEATTLE,
WASHINGTON.

SADIRON-HOLDER.

1,394,998.

Specification of Letters Patent. Patented Oct. 25, 1921.

Application filed February 2, 1921. Serial No. 441,794.

To all whom it may concern:

Be it known that I, IRA LEE, a citizen of the United States, residing at Seattle, in the county of King and State of Washington, have invented a certain new and useful Improvement in Sadiron-Holders, of which the following is a specification.

This invention relates to sad-iron holders which are adapted to be interchangeably used as a wall bracket, or as a stand upon an ironing board or table top.

The object of my invention is the provision of an inexpensively constructed device of this character which will be convenient to use and afford a holder in which a hot iron may be placed with an absence of danger of setting on fire or scorching the support to which the holder is attached.

The invention consists in features of construction and the combination thereof in a sad-iron holder as hereinafter described and claimed.

In the accompanying drawings illustrating the preferred embodiment of the invention,

Figure 1 is a front elevation of the holder and showing by broken lines an iron supported thereby. Fig. 2 is a rear elevation of Fig. 1 with a portion of the backing piece broken away. Fig. 3 is a longitudinal sectional view taken substantially through 3-3 of Figs. 1 and 2 and indicating a sad-iron by broken lines. Fig. 4 is a perspective view of spring clamping device of the holder, shown detached.

The holder illustrated in said drawings consists of a hollow body adapted to be detachably held in spaced relations to a vertical wall or above a table top, and is provided with resilient sad-iron engaging devices.

Said body, denoted generally by reference numeral 5, is desirably of an oblong shape and constructed of pressed sheet metal.

As shown, the body 5 comprises a face plate 6 having a peripheral flange 7 surrounding a back plate 8 and to which the latter is secured by flange-ears 9 as shown in Fig. 2.

The back plate 8 has stamped from the upper and lower portions thereof legs 10 and 11 which are bent in reverse direction to afford feed elements 10¹ and 11¹.

From the back plate 8 are also stamped side legs 12 having laterally directed feet elements 12¹. The feet elements 10¹ and 11¹

are provided with key-hole shaped apertures 10² and 11² for engaging headed screws or nails, as 13 Fig. 3, protruding from a table top or a vertical wall for engaging the holder to the same.

Openings 14 obtained by stamping said legs from the rear plate 8 serve, supplemental to vent holes 14¹, for the passage of air into and from the chamber 15 of the body for rendering the latter cool.

As an additional safeguard against accidental fire a sheet 16 of asbestos, or other poor heat conducting material, is desirably secured to the back of the body as by tongues 17 stamped from the plate 8.

The front wall or face plate 6 of the body is provided with a pair of transversely arranged slots 18 adjacent to the upper end of the body and a second pair of similarly arranged slots 19 is provided near its lower end. The iron holding device proper, hereinafter designated as the "cage," is preferably formed of a single piece of spring wire which is bent to provide centrally of its length a loop or loops 20 and arms 21 extending therefrom to bends 22, the above named parts of the cage are housed within the body chamber 15 as shown by dotted lines in Fig. 1 and by full lines in Fig. 3.

From the bends 22, post elements 23 extend outwardly through slots 19 to bends 24, thence by longitudinal elements 25 to bends 26 wherefrom tie elements 27 extend through slots 18 and terminate in hook shaped ends 28 which take against the face plate 6 within the chamber 15. The associated cage elements 23, 25 and 27 constitute wing members, one at each side of the longitudinal axis of the body, and are yieldingly held by the resiliency of the loops 20 to have the post 28 which take against the face plate 6 within the chamber 15. The associated cage elements 23, 25 and 27 of each wing bear against the inner ends of the respective slots 19 and 18. The lengths of said post and tie elements are such that when the body B of an iron, denoted by broken lines in Figs. 1 and 3, is juxtaposed with the face plate 6, the longitudinal elements 25 of the wings will overlay the iron body.

To obviate the polishing face of an iron adhering to the face plate 6 of the holder said plate is desirably corrugated by the provision of longitudinal ridges 29 and grooves 30.

For suspending the "cord" connections of an electric iron, when the device is ap-

plied to a wall, a hook 31 is advantageously attached to the lower foot 11¹.

For operation my device is secured by means of screws 13, Fig. 3, to a table or 5 against a vertical wall with the legs 10, 11 and 12 retaining the body member 5 away from the same. The iron is introduced point end first, through the opening obtaining between the post elements 23 of the cage 10 wings thereby spreading the latter apart until the heel end of the iron passes beyond such post elements, whereupon the resilient power of the loops 20 and arms 21 act to restore the wings to their normal positions in 15 which they are represented in Fig. 1. When this occurs the iron is engaged beneath the longitudinal elements 25 and between the tie elements 27. When the device is used in a vertical position attached to a wall, the post 20 elements 23 serve as bracket supports engageable by the heel end of the iron to bear the weight of the iron. To withdraw the iron the operator simply moves the iron, point first, through the opening between the 25 stay elements 27 to spread that end of the wings sufficiently apart for the egress of the iron.

The device is of inexpensive cost and convenient to use.

30 What I claim is,—

1. A sad-iron holder comprising a hollow body portion, wing devices extending therefrom and coöperating with said body to support a sad-iron in either an upright or horizontal position, and resilient means provided 35 interiorly of said body and serving to connect said wing devices with each other for relative movements with respect to each other and laterally of said body portion.

40 2. A sad-iron holder of the character described, comprising a hollow body having

slots in the face thereof, supporting legs extending from the rear of said body, a wire device provided with a spring portion interiorly of the body and extending therefrom through said slots to afford separable wing members exteriorly of the body to receive and support a sad-iron.

3. A sad-iron holder of the character described comprising a body provided with 50 rearwardly extending supporting legs, wing devices provided at opposite sides of the longitudinal axis of said body, and resilient means connected to said wing devices for 55 yieldingly holding the latter to afford a sad-iron retaining means, said wing devices being movable laterally by the sad-iron when progressively inserting and withdrawing the same into and from the space between the wing devices.

4. A sad-iron holder having a hollow body portion provided in the front wall thereof with two pairs of spaced slots, one pair of said slots being disposed adjacent to the top and the other pair of slots being disposed 65 adjacent to the bottom of said body, and means coöperating with said body for releasably connecting a sad-iron to the latter, said means consisting of a single piece of 70 spring wire which is bent to provide a spring element within the body, branch elements projecting therefrom through the lower of said slots thence upwardly to bends wherefrom the respective branches extend through the upper slots and terminate in 75 hook shaped ends within the body.

Signed at Seattle, Washington, this 28th day of January, 1921.

IRA LEE.
